US00D625535S

(12) **United States Design Patent**
Cattacin et al.

(10) **Patent No.:** **US D625,535 S**
(45) **Date of Patent:** **** Oct. 19, 2010**

(54) **PAPER DISPENSER**

(75) Inventors: **Gilles Cattacin**, Colmar (FR); **Nicolas Pommier**, Balgau (FR); **Yoann Denis**, Selestat (FR)

(73) Assignee: **Georgia-Pacific France** (FR)

(**) Term: **14 Years**

(21) Appl. No.: **29/316,134**

(22) Filed: **Aug. 26, 2009**

(30) **Foreign Application Priority Data**

Mar. 26, 2009 (EM) 001114946

(51) **LOC (9) Cl.** **20-02**

(52) **U.S. Cl.** **D6/518**
